UNITED STATES PATENT OFFICE.

FREDERICK W. COLE, OF NEWTON HIGHLANDS, MASSACHUSETTS, ASSIGNOR TO GAME-WELL FIRE ALARM TELEGRAPH COMPANY, OF NEW YORK, N. Y., A CORPORATION OF NEW YORK.

SIGNAL-BOX.

1,210,765.

Specification of Letters Patent. Patented Jan. 2, 1917.

Application filed November 24, 1915. Serial No. 63,823.

To all whom it may concern:

Be it known that I, FREDERICK W. COLE, a citizen of the United States, residing at Newton Highlands, in the county of Middlesex and State of Massachusetts, have invented an Improvement in Signal-Boxes, of which the following is a specification.

In fire-alarm signal-boxes, as usually constructed, the several instrumentalities contained therein, such as the signaling-mechanism, non-interference magnet, manual-key and sounder, are adapted to be arranged in the box-circuit in series relation when the box door is open and the signaling-mechanism is operating. In silently testing these boxes, it is customary to change the relative arrangement of these instrumentalities, by dividing the circuit, so that the sounder or bell-magnet, shall be arranged in one branch, and the other instrumentalities, including the signaling-mechanism, shall be arranged in another branch, or in other words, the sounder and the other instrumentalities shall be arranged in multiple relation. Such change is or may be accomplished by making electrical connections between the terminals of the box-circuit and points in said circuit between the sounder and the other instrumentalities, so that the current has two paths, in one of which the sounder is included, and in the other of which the other instrumentalities are included, and then opening the box circuit between said points of connection. When the arrangement of the box circuit is thus effected, the box may be tested by operating the signaling-mechanism in the regular way, the sounder correctly responding to the regular signal, but said signal is not sent over the main circuit.

This invention has for its object the construction of a switch-element which is made as a unit, it having a single operating-member adapted when in one position to arrange the box-circuit in normal condition with the several instrumentalities arranged in series relation therein, so that the box may be operated and the signal sent over the main-circuit in the regular way; and when in another position to rearrange the box-circuit to form two branches, one branch in-

cluding the signaling-mechanism, non-interference magnet, and manual-key, and the other including the tapper-magnet or sounder, a multiple relation with the instrumentalities. The construction and arrangement of the component parts of the switch-element is such that these results may be obtained by a simple pulling movement of the operating-member, and the simplification of these parts, whereby these results are obtained with positiveness, and the continuity of the main-circuit maintained, embodies the gist of this invention.

Figure 1 is a bottom plan view of a testing-switch embodying this invention the parts being in their normal position. Fig. 2 is a side elevation of the same. Fig. 3 is a bottom plan view similar to Fig. 1, the parts being moved into position to make electrical connections with the box-circuit preparatory to opening said circuit, so as to maintain the continuity of the main-circuit. Fig. 4 is a similar bottom plan view, the parts being in position to open the box-circuit between the instrumentalities contained therein, so as to arrange said instrumentalities in multiple relation. Fig. 5 is a diagrammatical view of a fire-alarm box-circuit and the instrumentalities ordinarily contained therein and having a testing-switch embodying this invention.

10 represents the box-circuit having its terminals at 11 and 12, respectively, the terminals of the main-circuit 15 being connected with said terminals 11 and 12. In said box there is connected, as here shown, the ordinary instrumentalities usually provided in a fire-alarm box, as for instance, the signaling-device 20, indicated by the signal-wheel and signal-key, the non-interference magnet 21 and the sounder 22, or in lieu thereof a bell or tapper-magnet. This box-circuit is normally closed and forms a part of the main signal-circuit, and the several instrumentalities are arranged in series relation therein, although shunts are usually provided for some or all of these instrumentalities, adapted to be opened by the opening of the box-door, or to be operated by the signaling-mechanism, but as said shunts form no part of the present invention

they are not herein illustrated, as to all intents and purposes, when testing the box, the box-door is opened and at such time these instrumentalities are arranged in series relation.

For the purpose of silently testing the box, it is herein designed to rearrange the several instrumentalities to bring them into multiple relation, certain of the instrumentalities being arranged in one branch thereof, and others in another branch thereof, and to effect this rearrangement without disturbing the continuity of the main-circuit, suitable electric connections and a unitary switch-element being employed. As here shown, there is provided circuit connections or wires 30 and 31, which are connected, respectively, with the terminals 11 and 12 at one end, and adapted to be connected 20 with the box-circuit at their other ends, at points between the instrumentalities therein contained, and a unitary switch-element is provided for making these connections, and thereafter for opening the box-circuit between the connected points.

The unitary switch-element here shown comprises a base 40, a pair of contact-members 41 and 42, here shown as resilient contact-pens attached thereto at one end, and 30 having their free ends separated a short distance and arranged for movement laterally in a direction away from each other, and another pair of similarly-constructed contact-members 43 and 44 attached at one end to 35 the base, and having their free ends normally in engagement with each other, and arranged for movement laterally in a direction away from each other to separate them. The contact-pens 41, 42, are made quite 40 short, and the contact-pens 43, 44, quite long, comparatively, and the pens 41, 42, are arranged inside of or between the pens 43, 44, and in approximately the same plane, so that as the pens 41, 42, are moved laterally 45 in a direction away from each other they will first engage, respectively, the adjacent pens 43, 44, and upon further lateral movement will cause the separation of said pens 43, 44. The switch-element also comprises 50 a plunger having a stem 45, a hand-piece 46, secured to said stem by which to slide it longitudinally, and a laterally extended lug 47, having a curved engaging-face. This lug is arranged between the contact-members 41, 55 42, and is adapted by a sliding movement of the plunger in an outward direction to engage said contact-members and move them laterally into engagement with the contact-members 43, 44, and by further movement 60 in the same direction to cause said contact-members 41 and 42 to move farther laterally and to correspondingly move laterally and separate the contact-members 43 and 44. The circuit-wires 30 and 31 are connected,

respectively, to the contact-members 42 and 65 41, and the contact-members 43 and 44 are connected in the box-circuit, and serve to maintain said circuit closed at this point. This switch-element is associated with the box-circuit at a point between the signaling-device and non-interference magnet on the one side and the sounder or other signal-responding instrument on the other side, and when the plunger is operated, these instrumentalities which were in series relation are 70 rearranged into multiple relation, and the continuity of the circuit maintained, as it will be noted that the circuit connections 30 and 31 are first connected with the box-circuit at points between the instrumentalities 75 30 by the contact-members 41, 42, engaging the contact-members 43, 44, and then the box-circuit is opened between said connected points, by the separation of the contact-members 43, 44.

The plunger is made long enough to be engaged by the door of the box when in normal position, and when the box door is opened, it may be drawn out to move the short contact-members laterally from normal and subsequently restored to normal by the closing of the box-door unless it has been previously restored by hand.

In the branch wire 30 is preferably included a resistance 50, and when the testing-switch handle is moved forward into testing position this is included in series with the bell or sounder magnet 22. The object of this is to increase the resistance through such path that a larger portion of the current shall pass through the branch to the non-interference magnet to insure its proper working at such time.

I claim:

1. A testing-switch element for signal boxes comprising a pair of long contact-pens connected with the line circuit and normally in engagement, a pair of short contact-pens connected with branch circuits and normally separated and arranged between said long contact-pens and adapted upon lateral movement from normal to engage, move laterally, and separate said long contact-pens, thereby to connect the branch circuits in multiple relation with the line circuit, while maintaining the continuity of the circuit, and an operating-member arranged for moving said short contact-pens laterally.

2. A testing-switch element for signal boxes comprising a pair of long contact-pens connected with the line circuit and normally in engagement, a pair of short contact-pens connected with branch circuits and normally separated and arranged between said long contact-pens and adapted upon lateral movement from normal to engage, move laterally, and separate said long contact-pens, thereby to connect the branch circuits in

multiple relation with the line circuit, while maintaining the continuity of the circuit, and a sliding operating-member having an outstanding lug arranged between the short contact-pens to move said short contact-pens laterally.

5 In testimony whereof, I have signed my

name to this specification, in the presence of two subscribing witnesses.

FREDERICK W. COLE.
